[57] **ABSTRACT**
Disclosed is an improved process for the liquid phase coking of spent wood pulping liquors wherein a part of the decoked effluent is flash vaporized to supply condensate for SO_2 absorption, thus eliminating the need to absorb SO_2 from an oxygen-containing flue gas into sulfite ion-containing coker effluent, thereby minimizing sulfite ion oxidation and reducing the amount of make-up chemicals required to reconstitute the pulping liquor.

The process is applicable to all acid sulfite pulping processes employing metallic ions such as sodium, calcium, magnesium, to ammonia-base sulfite and alkaline sulfite pulping liquors.

MINIMIZING SULFUR OXIDATION IN PULPING LIQUOR RECONSTITUTION

FIELD OF THE INVENTION

This invention relates to an improved process for treating spent-wood pulping liquors which results in the reconstitution of the wood pulping liquors with consequent savings in chemicals and in the substantial elimination of disposal and pollution problems.

DESCRIPTION OF THE PRIOR ART

In commonly assigned patent application U.S. Ser. No. 149,424 filed June 3, 1971, and now abandoned, it has been suggested to reconstitute metal ion-based pulping liquors by contacting SO_2 gas produced by coking the liquors with water condensed from the coked effluent which had been used to wash the coke produced and mixed with liquid effluent from the coker.

A portion of the sulfur present in the spent liquor remains in solution in the coker liquid effluent, largely as the desired sulfite ion, provided care is taken to exclude air in the processing steps. So readily does oxidation of sulfite to sulfate take place that sodium sulfite has long been used as an oxygen scavenger in boiler feed water treatment.

The remainder of the sulfur is present on the coke and is only incompletely removed in the washing step for sodium recovery. This bound sulfur on the coke must be recovered in the form of SO_2 from the flue gas when the coke is burned. Efficient combustion of the coke requires that excess combustion air be used, and consequently the flue gas may contain up to several percent of free oxygen. Absorption of SO_2 from this oxygen-containing flue gas by the coker liquid effluent would result in oxidation to sulfate of a portion of the sulfite dissolved in it. Since the sulfate form is inactive in subsequent pulping operations, any sulfite oxidized to sulfate represents a loss of sulfur to the process. Consequently, it is of benefit to avoid contact between the oxygen-containing flue gas and the sulfite-containing coker liquid effluent.

SUMMARY OF THE INVENTION

Absorption of SO_2 from the flue gas in condensate flashed from the main coker liquid stream avoids the undesirable contact of oxygen with the sulfite ion while accomplishing the desired purpose of recovering the SO_2 in the flue gas.

DETAILED DESCRIPTION OF THE INVENTION

In the physical embodiment of the invention diagrammed in the drawing, spent pulping liquor is raised to coker operating pressure of 1,000-1,100 psig by pump 10 and raised to coker operating temperature, 450° to 700°F, in the absence of added free oxygen under autogenous pressures of about 1,000 to 3,000 psig in fired heater 11. The partly coked liquor then passes to coker hold drum 12 for a period of 1 to 60 minutes, sufficient to complete the coking reactions and to allow the coke formed in these reactions to settle to the bottom of the hold drum. Gases formed in the course of the coking reactions are removed overhead through line 14. Clear coker liquid effluent is removed from the hold drum through line 15 and reduced in pressure by passage through throttling valve 16. Actual

pressure reduction through valve 16 will be determined by the liquid rate requirement of SO_2 absorber 23, but generally will be reduced to around 100 psig or less.

Flash drum 17 serves to separate remaining liquid phase material from the flashed vapor, which passes overhead to condenser 18. Gaseous products of the coking reactions pass through line 19 to join gases from coker hold drum 12 at point 20. Consequently, the combined gas stream then passes through line 21, to be burned in heater 11 to destroy malodorous sulfur compounds. Condensate from 18 passes through line 22 to SO_2 absorber 23.

Settled coke passes from the bottom of hold drum 12 to coke dewatering device 24. Liquid separated from the coke rejoins the main coker liquid stream through line 25 while a heavy coke slurry passes through line 26 to coke washer 27 for removal of soluble inorganics. Washed coke passes to a second coke dewatering device 28 and then to coke dryer 29. Here residual water is evaporated from the coke by hot flue gas from heater 11. Dried coke passes through line 30, to be burned as fuel in heater 11.

Flue gas exits from coke dryer 29 through line 31 and passes to SO_2 absorber 23. Here SO_2 is removed by absorption in condensate from line 22. Flue gas, free of SO_2 , is vented through line 32 while SO_2 solution passes through line 33 to coke washer 27. Effluent from 27, containing SO_2 recovered from flue gas and sodium washed from the coke, rejoins unvaporized liquid from flash drum 17 at point 34. The recombined liquid stream, after addition of any make-up chemicals which might be required, is then returned to the pulping digesters.

The practice of the invention leads to a saving of from 20 to 100 percent in make-up chemicals.

To avoid gel-type coke formation where ammonia-base sulfite liquor is being handled in the present process, it is preferred to heat the spent pulping liquor rapidly at a rate of 110° to 150°F per minute in the temperature interval of about 350°F to about 550°F. This preferred feature is disclosed and claimed in our copending application Ser. No. 149,487, filed June 3, 1971.

To increase the rate of coking and to carry out such coking at a lower temperature, the pH of waste alkaline liquors may be lowered to the range of about 7 to about 3 by adding sulfur dioxide to the waste liquor either as free SO_2 or as an aqueous solution of SO_2 . This preferred feature is disclosed and claimed in our copending application Ser. No. 149,425, filed June 3, 1971.

What we claim is:

1. In a process for liquid phase coking of spent sulfite-based pulping liquors to produce coke, flue gases including sulfur dioxide, and an aqueous sulfite-containing decoked effluent: the steps of: flash vaporizing a portion of said effluent; condensing said portion to form a condensate; immediately contacting said condensate with hot oxygen-containing flue gas containing sulfur dioxide formed by the drying and burning of said coke in excess combination air to form a sulfite solution thereby avoiding contact between said flue gas and said sulfite-containing effluent; and then washing said coke with said sulfite solution prior to drying and burning to remove soluble inorganic salts therefrom whereby chemicals are recovered for reconstitution of wood pulping liquors, and combining the said solution which now contains said salts with the unvaporized portion of said effluent.

2. The process of claim 1, wherein said flash vaporizing is effected by flowing said decoked effluent to a flashing zone and reducing pressure thereon to about 100 psig.

3. The process of claim 1, wherein the pH of said liquors is reduced to between about 7 and 3 before cok-

ing.

4. The process of claim 1, wherein said liquors are coked by heating at a rate of 110° to 150°F per minute in the temperature range of about 350°F to about 550°F.
